UNITED STATES PATENT OFFICE.

HARRY A. SEDGWICK AND PATRICK J. SHEEHAN, OF MILWAUKEE, WISCONSIN.

ELECTRODEPOSITION OF METALS.

Application filed June 27, 1921. Serial No. 480,785.

To all whom it may concern:

Be it known that we, HARRY A. SEDGWICK and PATRICK J. SHEEHAN, citizens of the United States, residing at Milwaukee, in 5 the county of Milwaukee and State of Wisconsin, have invented new and useful Improvements in Electrodeposition of Metals, of which the following is a full, clear, concise, and exact description, reference being 10 had to the accompanying drawing, forming a part of this specification.

This invention relates to electro-deposition of metals.

In our Patent No. 1,367,567, issued February 8, 1921, are disclosed certain improvements in electro-plating apparatus, which improvements have proven of great value industrially and commercially, and the present invention has among its objects that 20 of providing an improved method of electro-deposition involving certain features of said prior patent.

Another object is that of providing such a method enabling curtailment of the time, 25 current and mechanical power required to act upon a given quantity of material and whereof the finished output is materially improved.

Another object is that of providing such a method enabling material reduction in the 30 quantity of electrolyte required.

Another object is that of providing such a method involving a minimum of leakage loss of the plating current.

Another object is that of providing apparatus 35 for performance of the foregoing method.

Another object is that of providing such apparatus adapted to effect uninterrupted 40 electro-deposition and whereof the space requirements corresponding with a given rate of output are very considerably reduced.

Other objects and advantages will herein-after appear.

According to the present method, the heat 45 liberated during the electrolytic action is conserved and utilized for raising the temperature of the electrolyte, the quantity of the latter being reduced as far as permissible as hereinafter set forth, whereby the 50 liberated heat is sufficient to bring the electrolyte temperature approximately to the boiling point of water at which temperature the plating action is very materially facilitated and expedited.

Thus in practice the electrolyte, having

the material to be treated immersed therein, is entirely enclosed and is heat insulated from the surrounding air and from other heat absorbing agencies, the space between 60 electrodes of opposite polarity being reduced to thereby reduce the volume of electrolyte required, provision being made for effecting rotation or other agitation of the material undergoing treatment and also for 65 permitting escape of the electrolytically liberated gas.

In the accompanying drawing wherein is 70 illustrated a preferred embodiment of the invention in its physical aspects.

Fig. 1 is an end elevational view thereof;

Fig. 2 is a side elevational view partly in section of the same; while

Fig. 3 is a detail plan view of certain features of Fig. 2 as viewed from beneath.

In a preferred form of the present apparatus the material undergoing treatment is charged within one or more liquid tight containers, each having therein a quantity of electrolyte and also containing metal to be deposited, the container being composed of wood or other electrical and heat insulating material and having electrical connections with a suitable source of direct current such as to render the material undergoing treatment negative and the aforementioned body of metal to be deposited positive with respect to such current source, the container being revolved or rotated to effect agitation of the material for insuring even deposition of the coating of metal thereon.

Referring to the drawing, the same illustrates a plurality of containers 5 of the character aforescribed mounted upon and secured to a rotatable frame comprising substantially similar end members axially secured in spaced relation upon a rotatable shaft 6, the latter being in turn carried within bearings 7 and 8 of a suitable support indicated at 9. Each of said end members comprises as shown, a cylindrical section 10 and a web section 11 bolted together but insulated from one another, said cylindrical sections 10 being mounted directly upon the shaft 6.

In practice one, or optionally both, of the aforesaid sections 10 is furnished with gear teeth providing for driving of the aforescribed frame and containers by means of an electric motor 12 acting through 110 suitable reduction gearing indicated at 13.

Slip rings 14 and 15 are carried by the

respective web sections 11, said slip rings being provided with axially projecting feet 16 extending through suitable openings in the respective sections 10 is spaced and 5 insulated relation to the latter. Brushes 17 and 18 are adapted to co-operate with the respective slip rings for connecting the latter with a source of direct current, not shown.

- 10 Each of the web sections 11 is further provided upon its internally arranged face with a number of pairs of substantially radial flanges 19 equal to the number of containers provided, said flanges being located adjacent the peripheries of said web sections and the flanges of each section being arranged parallel with the corresponding flanges of the other. Each of the respective containers 5 is also provided with end 15 plates having correspondingly spaced and directed flanges 20 adapted to co-operate with the flanges of the aforescribed sections for support and securement of the containers by and between said web sections 20 of the frame and in electrical connection therewith and also providing for removal or replacement of the individual containers by radial movement of the latter. The containers 25 are normally held against outward movement with reference to the frame by means of hooks 21 having their reflexed ends engaged within suitable openings of the respective web members and having their opposite terminal portions extending 30 through suitably disposed openings in the corresponding end plates of the container, said terminal portions being screw-threaded to receive nuts or other releasable clamping and securing means.
- 35 Each of the aforementioned containers comprises a substantial fluid tight cylindrical structure or barrel having a peripheral portion 22 and end portions 23. In practice a section 24 of the peripheral portion 40 22 is formed distinct and separable from the remaining portion, thus affording access to the interior of the container, whereas clamping and securing means such as those illustrated are employed for releasably securing such removable section in place during 45 operation of the device.

An anode 25 comprising metal to be deposited is carried within and preferably centrally of each receptacle. Such anode may 50 be of any desired or preferred form but for convenience has been illustrated as substantially cylindrical and is preferably secured by means of rigid bolts or studs 26 and 27 screwed inwardly through the corresponding end plates of the container and into the adjacent terminal portions of the anode said studs being preferably secured in place by means of suitable nuts 28. The stud 26 of each receptacle is in electrical 55 contact with the adjacent end plate of such

receptacle, whereas the studs 27 are insulated from their associated end plates, the latter being cut away to space the same from said studs as shown. The end portions of each container are provided centrally with openings through which the respective studs 26 and 27 extend, said openings being normally closed by the adjacent end plates and one of the openings being of sufficient size to permit insertion or removal of the anode 75 therethrough.

Thus assuming construction of the container of insulating material the aforescribed arrangement provides for electrical connection of the anode to the one web section of the frame but insulated from the other web section when the container is mounted in operative relation.

A plurality of strips or bars 29 of conductive material such as copper are secured within and preferably closely adjacent to the interior surface of the several containers, all of said conductive strips of each container being electrically connected with one another, as by means of the conductive rings 30 and the latter being further connected with the corresponding web section as by means of current leads 31, but being insulated from the anode.

Thus assuming introduction into the several containers of a suitable electrolyte to fill the same up to a give or desired level, substantially as illustrated, and assuming charging of the containers with material to be treated, said containers being mounted and secured as shown, the current traversing the device is adapted to carry away metal from the anodes and to deposit the same upon such material undergoing treatment, the conductive strips 29 being so located and arranged as to insure electrical contact of such material with at least one of such conductive strips at all times, whereas due to the continuous rotation of the support carrying the receptacles the latter are caused to revolve continuously with consequent shifting of the material undergoing treatment whereby even and uniform deposition of metal thereon is promoted.

Since the aforescribed action of the device ordinarily involves liberation of considerable quantities of gas or vapor or both, the means now to be described are employed for permitting escape of such products from the interior of the containers without, however, permitting escape of the contained electrolyte or of the material undergoing treatment.

For such purpose each container is provided with a normally closed valve 32 adapted to open inwardly whereby any increase in fluid pressure within the receptacle tends to maintain the valve seated and to resist unwarranted opening thereof. Said valves are preferably so located with reference to

their respective containers as to bring all of said valves within the arc of a relatively small circle surrounding the shaft 6. Each valve is preferably provided with a hollow 5 stem 33 extending outwardly through the wall of the container and terminating in a beveled or rounded head 34, said stem having suitable openings 35 to be uncovered upon inward movement of the valve. A 10 spring 36 is compressed between said head and a portion of the container for resiliently holding the valve closed. Axially shiftable tappets 37 are carried by the adjacent web section 11 in register with the respective 15 heads 34 of the several valve stems, said tappets being preferably provided with enlarged heads for direct cooperation with said valve heads while springs 38 serve to hold said tappet heads outwardly with reference to the respective containers. A cam 20 member 39 is carried by the frame 9 in a relation to engage the tappets 37 successively and singly for forcing the latter toward their respectively associated valves each at a 25 stage of revolution of its container such that the valve is located above the surface of the contained electrolyte, as shown particularly in Fig. 2.

Thus, at each revolution of the device 30 the valve of each container is opened for permitting escape of the liberated gas or vapor, the aforementioned springs serving to effect closure of the valve as soon as the tappet passes the cam 39, said springs further acting in conjunction with fluid pressure to prevent unwarranted opening of the valve.

In the operation of the complete device the containers are charged successively with 40 electrolyte and material to be treated and are secured upon the frame. As soon as one or more of the containers is so charged and mounted, current is passed continuously through the circuit of the slip rings. When 45 all or the desired number of containers are so charged, the motor 12 is started for effecting rotation of the device. After operation of the device for the necessary period, said motor is stopped and a container, preferably the one first charged, is removed, dumped and recharged, a freshly charged container being preferably substituted for the one removed. Such operation may be effected in a few minutes or even in a few 50 seconds under favorable conditions and does not necessitate cutting off the plating current from the other containers.

By this means the device is adapted to operate continuously whereby its output is 55 greatly increased over that of devices which require interruption of the plating current during recharging.

Further the device involves no stationary electrolyte tank as distinguished from the 60 containers which hold the material under-

going treatment, each of said containers constituting in effect its own electrolyte tank. This arrangement further provides against the possibility of appreciable current leakage from one electrode to another 70 through a body of fixed electrolyte without passing through the material undergoing treatment.

Also since the electrolyte is contained within the individual receptacles and the 75 anodes are carried in close proximity to the material undergoing treatment the total quantity of electrolyte required is much less than that required in devices having an exteriorly arranged electrolyte tank, the 80 plating voltage and current required as well as the mechanical power necessary to effect rotation of the frame being correspondingly reduced.

The aforedescribed apparatus is thus well 85 adapted to performance of the present method since the use of the closed containers, composed preferably of wood, serve to prevent loss of the electrolytically liberated heat and to insure utilization of such 90 heat for raising the temperature of the electrolyte, the required quantity of the latter being much reduced, as described, whereby the resultant temperature rise thereof is further very materially increased. 95

Thus, under suitable conditions the temperature rises automatically and very rapidly approximately to the boiling point of water, under which conditions the electrolytic action is greatly expedited and facilitated and the character of the finished product improved particularly as regards uniform deposition of material over surfaces having depressions therein. 100

What we claim as new and desire to secure by Letters Patent is:

1. In a method of electro-deposition of metals, the step which comprises reduction of the electrical resistance of the electrolyte by conserving therein practically the 110 total quantity of heat generated as a result of passage of an electric current therethrough.

2. The method of electro-deposition of metals, which comprises subjecting the electrolyte to inherent conditions of temperature and pressure, and regulating the effect of certain of said conditions. 115

3. The method of electro-deposition of metals which comprises conservation and utilization of electrolytically liberated heat energy for raising the temperature of the electrolyte under conditions of pressure control to thereby facilitate and expedite the 120 electrolytic action. 125

4. The method of electro-deposition of metals which comprises conservation and utilization of substantially all the electrolytically liberated heat energy for raising 130 the temperature of the electrolyte while con-

trolling the pressure thereupon to thereby facilitate and expedite the electrolytic action.

5. The method of electro-deposition of metals which comprises utilization of electrolytically liberated heat energy for varying the temperature of the electrolyte approximately to that at which water boils while regulating the pressure thereupon, to thereby facilitate and expedite the electrolytic action.

6. The method of electro-deposition of metals which comprises segregation and heat insulation of the electrolyte to thereby 15 conserve the electrolytically liberated heat energy and utilization of the heat energy so conserved for raising the temperature of the electrolyte while controlling the pressure conditions to facilitate the electrolytic 20 action.

7. The method of electro-deposition of metals which comprises employment of a reduced quantity of electrolyte and segregation and heat insulation of the electrolyte to thereby conserve the electrolytically liberated heat energy and utilization of the heat energy so conserved for raising the temperature of the electrolyte while regulating the pressure thereupon to facilitate 25 the electrolytic action.

8. Apparatus for electro-deposition of metals, comprising a closed container to receive an electrolyte and material to be electroplated, electrodes in said container, and 35 means for controlling the pressure of gas evolved in said container during the electroplating operation.

9. Apparatus for electro-deposition of metals, comprising a support, a rotatable 40 shaft carried by said support, a plurality of substantially fluid tight containers arranged around and carried by said shaft, electrodes in each of said containers for connection with a suitable source of current, 45 means for admitting an electrolyte and material to be treated into each of said containers, a valve on each of said containers for controlling the pressure therein, and means for rotating said shaft and containers.

10. Apparatus for electro-deposition of metals, comprising a support for a rotatable shaft, a plurality of fluid tight containers carried by said shaft, means for admitting 55 an electrolyte and material to be treated into each container, a body of metal to be electrically transferred arranged in each container and forming an electrode in contact with the electrolyte, another electrode arranged in each container in contact with said material, means for connecting said electrodes to a source of current, valves on said containers, and cooperating means on said support to actuate said valves when 60 said shaft and containers are rotated to

thereby regulate the pressure within said containers.

11. Apparatus for electro-deposition of metals, comprising a substantially fluid tight container to hold an electrolyte and loose solid material to be metal coated, a body comprising metal to be deposited carried within said container and in contact with said electrolyte, means for connecting said material and said anode with a suitable source of current, means for revolving said container to effect relative movement of the contents thereof and means for regulating the fluid pressure in said container. 70

12. Apparatus for electro-deposition of metals, comprising a substantially fluid tight container to hold an electrolyte and loose solid material to be treated, a body comprising metal to be electrically transferred carried within said container and in contact with said electrolyte, means for connecting said body and said material with a suitable source of current, means for moving said container to effect relative movement of the contents thereof and means permitting escape of gas from said container. 80

13. Apparatus for electro-deposition of metals, comprising a substantially fluid tight container to hold an electrolyte and immersed material to be treated, a body comprising metal to be electrically transferred carried within said container and in contact with said electrolyte, means for connecting said body and said material with a suitable source of current, means for rotating said container to effect agitation of the contents thereof, and means for periodically establishing and interrupting communication between the interior of said container and atmosphere to thereby permit escape of electrolytically liberated gas while preventing loss of liquid electrolyte. 90

14. The combination with a support, of a rotatable shaft carried thereby, electrically insulated frame members rigidly mounted upon said shaft, an electrolyte container to be carried by and between said frame members, said container having interiorly located electrodes in contact with the contained electrolyte but otherwise insulated from one another, said frame members and said container having co-operating flanges providing for support and securement of the latter upon the former and also providing electrical connections for said electrodes. 110

15. Apparatus for electro-deposition of metals, comprising a support, a rotatable shaft carried thereby, spaced end members axially connected to said shaft, a plurality of pairs of substantially radial flanges on the adjacent faces of said end members, a plurality of substantially liquid tight containers having means for engagement with said flanges, and means for holding said parts in engaging relation. 125

16. Apparatus for electro-deposition of metals, comprising a rotatable shaft, axially spaced web members carried by said shaft, a plurality of electrolyte containers arranged between and removably carried by said web members, a plurality of electrodes in each container, means associated with one web member for connecting one electrode in each container with a source of current, means associated with another web member for connecting another electrode in each container with a source of current, and means permitting removal of one or more of said containers from said web members without interrupting the flow of current to other of said containers.
17. Electroplating apparatus comprising a rotatable support for a plurality of electroplating tanks, and means permitting removal of certain of said tanks from said support during the electroplating operation without interrupting the electroplating operation of other of said tanks.
18. Electroplating apparatus comprising a horizontally rotatable support for a plurality of radially arranged electroplating tanks, a pair of electrodes in contact with an electrolyte in each tank, means connecting said electrodes with a source of current, and means for discontinuing the electroplating operation in one or more of said tanks without interrupting the electroplating operation in other of said tanks.

In witness whereof, we have hereunto subscribed our names.

HARRY A. SEDGWICK.
PATRICK J. SHEEHAN.
